STRINGED MUSICAL INSTRUMENT

John Dopyera, Los Angeles, Calif., assignor, by direct and mesne assignments, to Emil Dopyera, Rudolph Dopyera, Louis Dopyera, and Robert Dopyera, doing business under name Dopyera Brothers

Application August 16, 1937, Serial No. 159,351

5 Claims. (Cl. 84—296)

This invention relates to improvement in stringed musical instrument.

The general object of the invention is to provide a novel means for amplifying the sounds produced by the strings of a musical instrument.

A more specific object of my invention is to provide novel apparatus for transmitting vibrations from the bridge to a resonator in a stringed musical instrument.

10 A further object of the invention is to provide a stringed musical instrument including a plurality of resonators having novel connections to a bridge.

15 An additional object of my invention is to provide a novel resonator for use in a violin.

Other objects and the advantages of this invention will be apparent from the following description taken in connection with the accompanying drawings, wherein:

20 Fig. 1 is a top plan view of a violin embodying the features of my invention;

Fig. 2 is an enlarged fragmentary top plan view of the violin shown in Fig. 1 with portions thereof removed and portions broken away;

25 Fig. 3 is an enlarged section taken on line 3—3 of Fig. 1;

Fig. 4 is an enlarged section taken on line 4—4 of Fig. 1;

30 Fig. 5 is an enlarged section taken on line 5—5 of Fig. 1;

Fig. 6 is an enlarged top plan view of one of the fulcrum members; and

Fig. 7 is an enlarged section taken on line 7—7 of Fig. 6.

35 Referring to the drawings by reference characters I have indicated a violin embodying the features of my invention generally at 10. As shown the violin 10 comprises a body 12 which may be made of wood and of the usual shape, a

40 neck 13 having the usual fret board 13' thereon, a tail piece 14, a bridge 15 and the usual strings 16, 17, 18 and 19. The body 12 includes a peripheral wall 20, a bottom member 21 and a top member 22.

45 The top member 22 adjacent the neck end of the body has an aperture 23 therein and adjacent the tail end the body has an aperture 24 therein. Surrounding the apertures 23 and 24 on the underside of the top 22, I may provide a reinforcing ring 25 and 26 and in the top member surrounding the apertures 23 and 24, I provide recesses 27. As shown, the aperture 24 is of greater diameter than the aperture 23.

Positioned between the aperture 23 and 24, I 50 show a pair of spaced partition members 28 and

30 which extend transversely across the body 12 from side to side and from top to bottom.

Positioned in the aperture 23, I provide a metal resonator 31 and in the aperture 24, I provide a similar metal resonator 32. Each of the resonators 31 and 32 includes a peripheral foot or rim portion 33, a concave portion 34 and a convex portion 35. The concave portion preferably includes a plurality of circumferential beads indicated at 36. On the underside of the convex portion 35 at the center thereof I provide a thickened washer 37 having a bolt 38 extending therethrough and having a nut 39 thereon engaging the outer face of the resonator. The washer 37, the bolt 38 and the nut 39 are all preferably 10 coated with silicate of soda or similar material.

15 The resonators 31 and 32 are positioned in their respective apertures with the foot portions 33 thereof positioned in the recesses 27 and with the convex portions extending outward. The 20 foot portions 33 are preferably secured to the bottom of the recesses 27 as by a suitable adhesive and have a plurality of spaced apertures 40 therein.

25 Mounted on the resonator 31, I provide a metal vibrator rod 41 and mounted on the resonator 32, I provide a similar rod 42. The rod 41 is of greater length than the rod 42 but otherwise they are alike so but one will be described in detail. As shown the rod 42 includes an intermediate inverted V-shaped portion 43, a solid securing end 44 having an aperture 45 therethrough and a solid bridge end 46 having spaced upstanding lips 47 and 48 thereon.

30 The lip 47 has a threaded aperture 49 therein in which a bolt 50 having a lock nut 51 thereon is positioned. Intermediate the end portions 44 and 46 on opposite sides of the rod I provide elongated recesses 52 (see Figs. 3 and 7). The aperture 45 of the rod 42 receives the bolt 38 of 40 the resonator 32 and is secured thereto by a nut 53. Likewise the rod 41 is similarly secured to the resonator 31.

35 To support the outer portions of the rods 41 and 42, I provide fulcrum support members 54 and 55 both of which are of similar construction so but one will be described in detail. As shown in Figs. 6 and 7 the support member 54 includes a plate portion 56 having enclosed sides 57 to form a dovetail rail. Adjacent one end the plate 50 56 has a pair of spaced integral upstanding lugs 58 thereon having aligned threaded apertures 59 therein. Positioned in each of the apertures 59, I provide bolts 60 the inner ends of which are pointed as at 61 and the outer ends have a 55

screw driver slot 62 therein. The bolts 60 are adapted to be locked in a set position by lock nuts 63 thereon. The plate portion 56 of the device 54 is positioned in a dovetailed recess 64 in a plate member 65. The member 65 rests on the top 22 of the body 12 and includes a depending leg 66 which extends through an aperture 67 in the top 22 and is shown as secured to the partition 30 by bolts and nuts 63.

10 Adjacent the end opposite the lugs 58 the plate 56 has a pair of spaced elongated apertures 69 therein in which bolts 70 are positioned and extend into suitable threaded apertures in the member 65. Thus the fulcrum support member 15 54 can be moved relative to the plate 65 and clamped in an adjusted position by tightening the bolts 70.

When the rods 41 and 42 and the support members 54 and 55 are operatively assembled 20 the pointed ends 61 of the bolts 60 are positioned in the recesses 52 of their associated rods as clearly shown in Fig. 7.

The bridge 15 is positioned on the ends 46 of the rods 41 and 42 between the lips 47 and 48 and 25 between the lips 47 and the bridge, clamp plates 72 are provided. The bolts 59 are tightened against the plates 72 which in turn clamp the bridge against the lips 48 thereby firmly securing the bridge on the rods.

30 Positioned over the resonators 31 and 32, I provide metal cover members 73 and 74. Each of the covers 73 and 74 comprises a central convex portion 75 and a peripheral foot portion 76. The convex portions 75 of the covers 35 have a plurality of sound emitting apertures 77 therein and the foot portions 76 have a plurality of spaced apertures 78 therein matching the apertures 49 in the resonators. Furthermore, the covers have elongated apertures 79 therein 40 to provide clearance for the rods 41 and 42. The covers 73 and 74 are shown as secured to the body 12 by a plurality of screws 80 which are positioned in the cover apertures 78 and the resonator apertures 49 and enter the top 22 and 45 the reinforcing rings 25 and 26. Thus the covers 45 assist to secure their associated resonators to the body 12.

When the strings of the violin 10 are tightened they exert a downward pressure on the bridge 50 15 which in turn exerts a downward pressure on the outer ends 46 of the rods 41 and 42 which due to the pivot bolts 60 exert an upward pull on the resonators.

When the treble strings 18 and 19 of the violin 10 are played they influence the resonator 31 55 more than they do the resonator 32 and when the base strings 16 and 17 are played they influence the resonator 32 more than they do the resonator 31. Thus the resonator 31 is 60 preferably constructed to respond to the treble vibrations and the resonator 32 is preferably constructed to respond to the base vibrations.

The partitions 29 and 33 form a dead air space 65 between the resonators 31 and 32 thereby lessening the degree to which one resonator can set up sympathetic vibrations in the other.

The top 22 like the covers 73 and 74 has a plurality of spaced round emitting apertures 81 therein.

From the foregoing description it will be apparent that I have provided a novel stringed musical instrument construction which is simple in construction and highly efficient in use.

Having thus described my invention, I claim:

1. For use in a musical instrument, a pair of laterally spaced circular resonators, a bridge, 10 means connecting said bridge and said resonators, said bridge being adapted to support playing strings, said connecting means being disposed nearer to the center of one resonator than the center of the other resonator so that the bridge 15 affects one resonator more than the other.

2. For use in a musical instrument, a pair of laterally spaced resonators, a rod fixed to the central portion of each of said resonators, said rods being of different lengths, a bridge, the end 20 of one of said rods supporting one end of said bridge, the end of said other rod supporting the other end of said bridge and a pivotal support for each rod, said pivotal supports being located intermediate the length of each of said rods and 25 means to individually adjust the pivotal supports along the rods.

3. For use in a musical instrument, a pair of spaced apart resonators, a rod fixed to the central portion of each of said resonators, the rod 30 on one resonator being directed towards the other resonator and the rod on the other resonator being directed towards the one resonator, the rod on one resonator being shorter than the other rod, a bridge, the ends of said rods supporting the ends of said bridge and a pivotal support disposed intermediate and adjustable 35 along the length of said rods.

4. For use in a musical instrument, a pair of laterally spaced resonators, one of said resonators being larger than the other resonator, a rod fixed to the central portion of each of said resonators, each of said rods being directed towards the adjacent resonator, the rod on one resonator being shorter than the other rod, a 45 bridge, the free end of one of said rods engaging one end of said bridge, the free end of said other rod engaging the other end of said bridge and a pivotal support disposed intermediate and adjustable along the length of said rods. 50

5. For use in a musical instrument, a pair of laterally spaced resonators, a rod fixed to the central portion of each of said resonators, said rods being disposed in substantially parallel relation, a bridge, the free end of one of said rods 55 engaging one end of said bridge, the free end of said other rod engaging the other end of said bridge, a pair of fulcrum members, said members each including a base, said fulcrum having a pair of upstanding lugs thereon, said lugs having opposed apertures therein, pins threadedly engaging said apertures, said pins having pointed ends and said rods having opposed recesses receiving said pointed ends. 60

JOHN DOPYERA. 65
